C. C. HOWE

WRINGER

Filed Sept. 23, 1922

UNITED STATES PATENT OFFICE.

CHESTER C. HOWE, OF NEW KENSINGTON, PENNSYLVANIA.

WRINGER.

Application filed September 23, 1922. Serial No. 590,004.

To all whom it may concern:

Be it known that I, CHESTER C. HOWE, a citizen of the United States, residing at New Kensington, in the county of Westmoreland, State of Pennsylvania, have invented certain new and useful Improvements in Wringers, of which the following is a specification.

This invention is for an improvement in wringers, and relates particularly to tensioning means for the rolls and a quick release for such tensioning means.

The present invention proposes to provide a quick release for the rolls readily operable from either side of the wringer, which will efficiently hold the rolls under compression at normal times, but which will be easy to operate in an emergency.

The invention may be readily understood by reference to the accompanying drawings, in which:

Fig. 1 is a front elevation of so much of a wringer as is necessary to illustrate my invention;

Fig. 2 is a transverse vertical section in the plane of line II—II of Fig. 1;

Fig. 3 is a similar section with part of the frame broken away;

Fig. 4 is a top view of the releasing mechanism;

Fig. 5 is a detail view of one of the wringer parts.

In the drawings, A designates the upper part of a wringer frame, which is preferably made of metal and formed of two sections 5 and 6. The frame forms an upper cross portion or bridge 7 and depending sides 8. The sides provide supports for the rolls, the upper one of which is shown and designated 9. The ends of the roll shaft are received in the depending sides 8 in which they are movable vertically. Blocks 10, vertically slidable in the sides 8, provide bearings for the roller shaft. The shaft 45 may be geared to the lower shaft in the usual way by a gear wheel 11 at one end thereof.

Extending in the same direction as the roll is a leaf spring 12, having its ends extending into the side portions 8 and bearing on the blocks 10. By applying pressure to this spring, the rolls may be put under tension.

For this purpose, I provide a block 13

slidably retained in lugs 14 cast on the frame members. The upper end of this block projects through an opening provided in the top of the frame, and extending through the block is an opening which is threaded preferably throughout the lower portion thereof only. The block is of a peculiar cross-like shape, having longitudinal ribs 13^a and other ribs 13^b. The guideway provided by lugs 14 is such that the block is kept from turning therein.

Extending through the block and threaded therein, is a screw 15 having a winged handle 16 at its upper end. The lower end of the screw bears against the center of spring 12.

Formed in each of the members 5 and 6 is an opening 17, the openings being in alinement. Passing through the openings are the handle portions 18 of a releasing frame 19, which frame surrounds the block 13. The frame has trunnions 19^a that bear in parts of the lugs 14, as shown in Fig. 2, so that, upon the application of pressure to either of the handles, the frame may be rocked from its normal horizontal position. Springs 20 passed through the trunnions and secured in lugs 21 on members 5 and 6 may be used to urge the releasing frame back to horizontal position.

On the frame in vertical alinement with the trunnions and at each side of block 13, is a vertical arm or rib 22 which projects through the top of the frame and which is provided with lugs 23. When the frame is in a horizontal position, the lugs overhang ribs 13^a of the block 13, and prevent upward movement of the block. Consequently, when screw 15 is turned, in the proper direction, pressure may be applied to spring 12, block 13 being held against upward movement, due to the corresponding reaction on lugs 23 of the rocking frame. If the frame is rocked in either direction, arms 22 move in an arc and the lugs 23 are moved out of engagement with the tops of ribs 13^a, and the block is free to move upward, thereby relieving the pressure on the spring.

In order to limit the upward movement of the block, a pin 24 is provided therein, which projects into a guide 25 in the frame. When the pin reaches the end of the guide, the upward movement of the block is stopped.

The release as thus constructed is simple of construction, and may be operated in an emergency with very little effort. By reason of the two extensions 18 or handle portions, the release may be operated from either side of the wringer by downward or upward pressure. The handles are of sufficient length to enable the operator to bear down on them with his head or other part of his body, should he be unable to use his hands.

I claim as my invention:

1. A wringer including a supporting frame, a roll movable vertically in said frame, a vertically movable block in said frame, a shaft threaded in said block and having a handle portion projecting beyond the frame, means engaged by the threaded shaft for transmitting pressure from said shaft to the roll, and a latch for normally holding said block against upward movement, whereby pressure may be applied to said roll, said latch comprising a supporting member pivotally mounted in the frame on a horizontal axis and rotatable in either direction on its axis, and having arms thereon adapted to move through a vertical arc when the member is rocked, said latch being provided with means thereon for engaging the block when it is in normal position, said means being moved out of engagement with the block by the arcuate travel of said arms when the member is rocked in either direction from normal position.

2. A wringer including a supporting frame, a roll movable vertically in said frame, a vertically movable block in said frame, a shaft threaded in said block and having a handle portion projecting beyond the frame, means engaged by the threaded shaft for transmitting pressure from said shaft to the roll, and a latch for normally holding said block against upward movement, whereby pressure may be applied to said roll, said latch comprising a member pivotally mounted in the frame on a horizontal axis and movable in either direction in a vertical arc from normal position, said member having means thereon for normally engaging the block, said means being movable through an arc out of block engaging position when the member is rocked in either direction on its axis, and operating means for the latch.

3. A wringer including a supporting frame, a roll movable vertically in said frame, a vertically movable block in said frame, a shaft threaded in said block and having a handle portion projecting beyond the frame, means engaged by the threaded shaft for transmitting pressure from said shaft to the roll, and a latch for normally holding said block against upward movement whereby pressure may be applied to

said roll, said latch comprising a pivotally supported member mounted in the frame disposed transversely of the wringer frame and having handle portions projecting from both sides of the frame, said member having means thereon for normally engaging the block to hold it against upward movement, said means being movable through an arc out of block engaging position when pressure is applied to either of said handles sufficiently to rock said member.

4. A wringer including a supporting frame, a roll movable vertically in said frame, a vertically movable block in said frame, a shaft threaded in said block and having a handle portion projecting beyond the frame, means engaged by the threaded shaft for transmitting pressure from said shaft to the roll, and a latch for normally holding said block against upward movement whereby pressure may be applied to said roll, said latch comprising a pivotally supported member provided with a horizontally extending handle mounted in the frame to swing in a vertical arc and having means thereon for normally engaging the block, said means being movable through an arc out of block engaging position when the member is rocked by moving the handle either up or down from its normal position, and means for urging said member toward its normal position when rocked in either direction.

5. A wringer including a supporting frame, a roll movable vertically in said frame, a vertically movable block in said frame, a shaft threaded in said block and having a handle portion projecting beyond the frame, means engaged by the threaded shaft for transmitting pressure from said shaft to the roll, and a latch for normally holding said block against upward movement whereby pressure may be applied to said roll, said latch comprising a releasing member provided with an operating extension having horizontal trunnions thereon pivotally supported in the wringer frame whereby the frame may be rocked in a vertical arc, said releasing member having lugs thereon for engaging the block when the releasing member is in its normal horizontal position, said lugs being movable through an arc out of block engaging position when the releasing member is rocked in either direction, and springs engaging the trunnions for returning the member to its normal horizontal position.

6. A wringer comprising a frame, a roll movable vertically in the frame, a vertically reciprocable block in the frame having laterally extending ribs projecting therefrom, said block being non-rotatable in the frame, a shaft threaded through the block, means against which the lowermost end of the shaft contacts for transmitting pressure

to the rolls, a centrally apertured latch member mounted in the frame on a horizontal axis to swing in a vertical arc, and through which the block and threaded shaft 5 may pass, and block engaging extensions on said latch member normally engaging the ends of the ribs on said block, said extensions being movable in an arc out of en-

gagement with the ends of the ribs when the latch member is rocked in either direction 10 from normal, and an operating extension on said latch member.

In testimony whereof I affix my signature.

CHESTER C. HOWE.
